Primary Examiner — W. A. Teddy Falloway*Assistant Examiner* — Rani J Abdallah(74) *Attorney, Agent, or Firm* — Finnegan, Henderson, Farabow, Garrett & Dunner, LLP(57) **CLAIM**

The ornamental design for a bottle, as shown and described.

DESCRIPTION

FIG. 1 is a top, front perspective view of a bottle showing my new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a bottom plan view thereof; and,

FIG. 8 is a sectional view of FIG. 1 thereof.

The dashed broken lines in the figures illustrate portions of the bottle that form no part of the claimed design.

1 Claim, 8 Drawing Sheets(56)
